UNITED STATES PATENT OFFICE

ANTON H. NARROW, OF MEMPHIS, TENNESSEE.

TYPESETTING MACHINE.

Application filed December 2, 1921. Serial No. 519,440.

To all whom it may concern:

Be it known that I, ANTON H. NARROW, a citizen of the United States, residing at Memphis, in the county of Shelby and State 5 of Tennessee, have invented certain new and useful Improvements in Typesetting Machines, of which the following is a specification.

My said invention relates to an improvement in typographical machines such as linotype machines or intertype and it is an object of the same to provide means whereby the proper length of the type bars is indicated so that they can be cut off to the desired length without measuring each bar individually and cutting each one separately as is customary. In ordinary practice the bars as cast are of greater length than necessary and must be cut down to the proper 15 length. This is particularly true of display type in advertisements where the lines begin and end at varying distances from the margin so as to fit about a cut, or for other reasons. This is usually done by means of a 20 rotary saw the bars being cut off separately at the right-hand end of the bar, (or the left end of the line) and the length of the bars being determined individually by measuring from the right-hand end. Such a saw includes a gauge which can be set so as to cut 25 the bars off at the required length and particularly in case of display type the gauge must be set again and again, sometimes as often as there are type bars, because of the 30 varying length of the lines. By my invention this work is done away with and any convenient number of bars can be positioned on the table of the saw at one time and brought to proper cutting position readily 35 and quickly and the projecting ends (or slugs) cut off by a single relative movement 40 of the saw and the table.

In ordinary practice also when the make-up is being put into the form if any blank 45 spaces are to remain at the left end of the line blanks or quads must be put in when making up the form if the bars have been sawed off too short to provide such a space. By my invention every bar is sawed off at

exactly the right length and no quads are 50 necessary.

Referring to the accompanying drawings which are made a part hereof and on which similar reference characters indicate similar parts,

Figure 1 is a face view of my invention, and

Figure 2 a horizontal section.

In the drawings 10 indicates the right-hand vise jaw of a linotype machine and 11 60 a left-hand vise jaw. A row of matrices 12 is shown in position between the vise jaws ready for casting a line of type. According to my invention a hole is formed at 13 in the left-hand vise jaw into which the type metal 65 flows when the bar is cast, the jaw thus acting as a combined jaw and matrix. The jaw 11 is movable as usual according to the length of the line of type and if the first letter is to be spaced further from the margin 70 than in the ordinary line, as is common in display printing, a series of blank matrices may be inserted next the jaw. In this way the dot or projection formed at 13 will be 75 equally far from the end of each line of type to be set up in the form. The hole should be deep enough to provide a measure finding dot of a height that will permit ready application to a straight edge of some convenient type on the cutting-off machine, i. e., 80 it should ordinarily be deep enough to produce a dot higher than the characters on the printing surface, and the operator will take up any convenient number of type bars, in 85 his hands, even them up with their measure finding dots against a straight edge, run the saw across them and saw them all off at one time. The position of the dot is such that the saw will pass between it and the indications on the type bar, otherwise it would 90 print a period or other formation according to its shape. The hole may be drilled, cast or otherwise produced in the vise jaw.

No experience will be required in sawing off the bars, since the measure finding dot, 95 if properly located by the type setter, necessarily gives a line of precisely correct length. The type bar produced is shown in my ap-

plication No. 519,441 of even date herewith. It will be noted that the preferred form of the type bar has a measure finding dot of greater height than the type as illustrated 5 in said application.

Having thus fully described my said invention, what I claim as new and desire to secure by Letters Patent, is:

1. In a linotype machine, means for casting 10 a type bar and means for forming on the same an indication of the desired position of the ultimate position of the left end of the type bar, substantially as set forth.
2. In a linotype machine, means for casting 15 type bars and means for forming on each type bar an indication of the desired position of the end of the line, substantially as set forth.
3. In a linotype machine, means for casting 20 type bars and means for forming on each type bar an indication of the desired length of the bar, substantially as set forth.
4. In a linotype machine, means for cast-

ing type bars and means for forming on each type bar an upward projection at a distance 25 from the end of the line of printing characters and of greater height than such characters, substantially as set forth.

5. In a linotype machine a solid vise jaw having a hole in its lateral face spaced 30 from the end face thereof, substantially as set forth.

6. In a typographical machine, means for casting type bars with a slug adapted to be cut off, and means for forming on each type 35 bar a measure finding indication showing where the cutting operation is to be performed, substantially as set forth.

In witness whereof, I have hereunto set my hand and seal at Memphis, Tennessee, 40 this 23rd day of November, A. D. nineteen hundred and twenty-one.

ANTON H. NARROW. [L. S.]
